US0D1041617S

(12) **United States Design Patent** (10) **Patent No.:** **US D1,041,617 S**
(45) **Date of Patent:** **** Sep. 10, 2024**

(54) **NOZZLE**

(71) Applicant: **Telebrands Corp.**, Fairfield, NJ (US)

(72) Inventors: **Ajit Khubani**, Fairfield, NJ (US);
Mohan Rajasekaran, Watertown, CT (US)

(73) Assignee: **Telebrands Corp.**, Fairfield, NJ (US)

(**) Term: **15 Years**

(21) Appl. No.: **29/947,356**

(22) Filed: **Jun. 14, 2024**

Related U.S. Application Data

(62) Division of application No. 29/814,992, filed on Nov. 10, 2021, now Pat. No. Des. 1,032,783.

(57) **CLAIM**

The ornamental design for a nozzle, as shown and described.

DESCRIPTION

FIG. 1 is a top, front, and right side perspective view of a nozzle;

FIG. 2 is a front elevation view thereof;

FIG. 3 is a rear elevation right view thereof;

FIG. 4 is a left side elevation view thereof;

FIG. 5 is a right side elevation view thereof;

FIG. 6 is a top plan view thereof; and,

FIG. 7 is a bottom plan view thereof.

The long dash-short dash broken lines represent boundaries of the claimed design and form no part thereof. All other broken lines represent portions of the nozzle that form no part of the claimed design.

1 Claim, 6 Drawing Sheets

US D1,041,617 S
